UNITED STATES PATENT OFFICE.

LANVILLE A. BROWN, OF KANSAS CITY, MISSOURI

DESIGN FOR A BEDSTEAD.

51,329.

Specification for Design.

Patented Oct. 9, 1917.

Application filed August 22, 1917. Serial No. 187,679. Term of patent 14 years.

To all whom it may concern:

Be it known that I, LANVILLE A. BROWN, a citizen of the United States, residing at Kansas City, State of Missouri, have invented a new, original, and ornamental Design for Bedsteads, of which the following is a specification, reference being had to the accompanying drawings, forming part thereof.

The figure is a perspective view of a bedstead, showing my new design.

I claim:

The ornamental design for a bedstead, as shown.

LANVILLE A. BROWN.
